UNITED STATES PATENT OFFICE.

MAX M. SUPPES. OF ELYRIA, OHIO.

SAFETY-GATE FOR METAL-MIXERS.

1,006,700.

Specification of Letters Patent. Patented Oct. 24, 1911.

Application filed August 28, 1911. Serial No. 646,522.

To all whom it may concern:

Be it known that I, MAX M. SUPPES, a citizen of the United States, residing at Elyria, in the county of Lorain and State of Ohio, have invented a new and useful Safety-Gate for Metal-Mixers, of which the following is a specification.

My invention relates to a safety device for vessels or containers employed in handling and storing molten metal, and more particularly relates to a safety gate for preventing spilling of molten metal from such containers or vessels.

One object of my invention is to provide a safety gate or shutter for metal mixers and similar vessels whereby in cases of emergency spilling of metal from the pouring spout of such vessels is prevented and overcome and possible loss of life or damage to surrounding property thereby avoided and rendered practically impossible.

Another object of the invention is to provide novel means for operating or handling the safety gate by which the safety gate is manipulated and lowered into its operative position and is raised into its inoperative position in which it is ordinarily maintained.

Referring to the accompanying drawings forming part of this specification, Figure 1 is a side elevation of a portion of a metal mixer or receiver showing my improved safety device as applied for use on the pouring spout thereof. Fig. 2 is a front elevation of the apparatus shown in Fig. 1. Fig. 3 is a detail sectional side elevation of the pouring spout showing the safety gate in its lowered or operative position therein. Fig. 4 is a side elevation partly in section, showing one form of tripping mechanism adapted for use on the safety gate. Fig. 5 is an end elevation of the tripping mechanism shown in Fig. 4.

In the drawings, 2 designates a rotary vessel employed as a metal mixer or receiver for molten metal. The vessel is rotatably mounted upon suitable supports 3 and is provided with a pouring spout 4 through which the metal is emptied or poured from the mixer. A receiving spout is located on the opposite side of the vessel through which the metal is introduced into the mixer, and the vessel 2 and its spouts are provided with a refractory lining constructed in the usual manner. Mounted on the sides of the pour-

4 of the vessel so as to extend

vertically thereon are slides or ways 6 in which a sliding gate or shutter 7 is mounted to be vertically movable therein. A cross bar or arm 8, arranged to extend across and between the upper ends of the ways 6 is provided to form a support for the sheave wheel 9 which is rotatably secured by a pin or shaft 10 on the bracket bearings 11 mounted on the cross arm 8.

A cable or other flexible connection 12 is secured by one end to the upper edge of the gate or shutter 7 and passes around the sheave wheel 9, the other end of this cable being provided with a link 13 by which the gate is held in its raised or inoperative position. The link is arranged to connect with the finger 14 of the tripping lever 15 which is pivotally mounted on the support 16 secured to one of the sides of the pouring spout 4. The upper end of the tripping lever 15 is connected to one end of a wire rope or other flexible connection 17.

As in the apparatus shown, (which has a maximum capacity of 1300 tons of molten metal), the gate 7 is comparatively large and too heavy to be readily manipulated manually, a lifting motor 18 such as the small electric motor shown, is provided to lift the gate from its operative or spout closing position into its inoperative or normal position. This motor 18 is geared or otherwise operatively connected to a winding drum 19 having one end of a cable or other flexible connection 20 secured thereto. The opposite end of the cable 20 is provided with a hook 21 which is adapted, when the cable 20 is unwound from the drum 19, to engage with the link 22, which is provided adjacent to one end on the flexible connection 12 by which the gate or shutter 7 is lifted and held in its raised position.

The operation of the apparatus is as follows:—The hook 21 on the rope 20 is connected with the link 22 in the gate supporting cable 12 and the motor 18 is then actuated to wind the rope 20 on the drum 19 so as to lift the gate 7 into the position shown in Figs. 1 and 2. The latch lever 15 is then moved manually so that the finger 14 on this lever engages with the link 13 on one end of the cable 12 so as to secure and hold the gate 7 in its lifted position. The vessel or mixer is then rotated or tilted as often as desired in successively removing portions 110 of the metal contained therein to other receivers or ladles. Sticking or other acci-

dent to the mixer turning mechanism preventing backward tipping of the mixer results in great liability of spilling large quantities of the molten metal in the mixer, 5 and molten metal, when spilled, is liable to cause injury and loss of life, as well as greatly damage surrounding property. In such case when control of the mixer is lost temporarily or an accident or breakdown of 10 the tilting or rocking mechanism occurs, an operative will grasp the wire rope 17 connected to the upper end of the latch lever 15 and by a pull will detach and release the cable 12. The weight of the gate 7 will then 15 cause it to quickly slide downwardly in the ways or slides 6 and shut off the flow of metal from the mixer 2 through the spout 4. The mixer is rocked or tilted backwardly as soon as may be so that no more metal will 20 flow therefrom. The motor 18 is then again employed to lift the gate or shutter 7 and the link 13 on the end of the cable 12 connected to the gate 7 is again engaged by the finger 14 on the tripping lever 15 so as to 25 maintain the gate 7 in its raised or lifted position in readiness for use until such time as necessity caused by accident or breakage requires it to be lowered or allowed to drop. In such case the above described operations 30 are repeated.

The advantages of my invention will be apparent to those skilled in the art. By the application and use of the safety gate on the pouring spout of rocking or tilting vessels 5 containing large quantities of molten metal the liability of serious injuries or loss of life and great damage to surrounding property in case of accident is prevented and overcome.

0 The apparatus is simple and is easily kept in repair.

Modifications in the construction and arrangement of the parts may be made without departing from my invention as defined 5 in the claims. Instead of using a rotary motor as shown for raising the safety gate, a fluid pressure cylinder or other lifting mechanism may be employed. When the necessary size of the gate is small enough, 0 the lifting motor may be dispensed with. The construction of the latch and tripping

mechanism may be changed and other modifications may be made without departing from my invention as defined in the claims.

I claim:

1. The combination with a vessel for handling molten metal having a pouring spout thereon, of a sliding safety gate movable into and out of said spout and means for detachably holding the gate out of said 60 spout.

2. The combination with a vessel for handling molten metal having a pouring spout thereon of a sliding safety gate movable into and out of said spout, means for detachably 65 holding the gate out of said spout and means for manually operating said detachable holding means to release the gate.

3. The combination with a vessel for handling molten metal having a pouring spout, 70 of a sliding safety gate movable into and out of said spout, tripping mechanism to hold said gate out of said spout and means for actuating the tripping mechanism to release and permit downward movement of 75 the gate into said spout.

4. The combination with a vessel for handling molten metal having a pouring spout, of a sliding safety gate movable into and out of said spout, tripping mechanism to 80 hold said gate out of said spout, means for actuating the tripping mechanism to release and permit downward movement of the gate into said spout and power means for lifting the gate out of said spout into engagement 85 with said tripping mechanism.

5. The combination with a vessel for handling molten metal having a pouring spout, a sliding safety gate movable into and out of the spout, and ways or slides for the gate, 90 of means for holding the gate in its raised inoperative position and tripping mechanism arranged when actuated to release and permit descent of the gate into the pouring spout of the vessel to shut off flow of metal 95 therefrom.

In testimony whereof, I have hereunto set my hand.

MAX M. SUPPES.
